UNITED STATES PATENT OFFICE.

SOLOMON H. GOLDBERG, OF CHICAGO, ILLINOIS.

COMBINED CONTAINER AND EXHIBITING DEVICE.

1,330,259.

Specification of Letters Patent. Patented Feb. 10, 1920.

Application filed June 14, 1915, Serial No. 34,042. Renewed May 26, 1919. Serial No. 299,941.

To all whom it may concern:

Be it known that I, SOLOMON H. GOLDBERG, a citizen of the United States, residing in Chicago, in the county of Cook, State of Illinois, have invented certain new and useful Improvements in Combined Containers and Exhibiting Devices, of which the following is a specification.

This invention relates to a combined container and exhibiting device and more particularly to a container by means of which a plurality of hairpins or other articles can be distributed and one or more of the contents exhibited.

Among the salient objects of the invention are to provide a device of the character referred to which can be formed from a single piece of cardboard or like material; to provide a construction in which a plurality of hairpins or other articles can be packed in assorted sizes, and if desired, distributed by mail or otherwise without danger of any of the articles dislodging from their seats and being lost; to provide a construction in which the hairpins or other articles can be quickly and easily inserted and withdrawn and the assorted sizes stored separately when not in use; to provide a construction in which a plurality of slots in one of the flaps allow the lower ends of the articles to rest against the lower edge of the pocket formed in return bending the inner flap, this pocket being capable of containing a supply of articles additional to those exhibited; and in general to provide a construction which can be economically manufactured and assembled, in which the articles will be safely carried and will clearly present to the view of the person opening the outer flap one or more of the articles contained therein.

In the drawings:

Figure 1 is a plan view of the blank before folding.

Fig. 2 is a perspective view showing the articles as they are exhibited when the package is opened.

Fig. 3 is a cross section through the container in its folded or shipping position.

Referring in detail to the particular embodiment of my invention shown in the drawings, 1 designates a blank preferably cut from cardboard sufficiently stiff to hold its shape when bent and having central sections 2 and 3, the former of which is provided with an end flap 4 and the latter with an end flap 5. This last mentioned end flap

has a tongue 6 ending in a tapered point 7, the point and tongue in the folded position of the device extending through a slot 8 formed in the central section 2. The latter 60 section is also provided with side flanges 9 and 10.

In assembling the blank, the end flap 4 is folded upon the central section 2 and the side flanges 9 and 10 then fold inwardly on 65 the edges of the end flap 4 and is secured thereto in any suitable manner such as by bending them over and gluing them to the edge portions of the end flap 4, so as to hold the latter adjacent the section 2. The end 70 flap 4 is provided with one or more apertures or slots 11, which form the seats for the pins, these seats being preferably curved to aid in directing the ends of the hairpin into engagement with the slot. When inserted through the slots 11, the articles are 75 pushed down until their lower ends abut against the return bent edge 12 formed at the lower end of the flange or pocket.

Thus as shown in Fig. 2 where a plurality 80 of articles of different sizes such as the hairpins 14, 15, 16, 17 and 18 are used their upper ends are disclosed in inclined position so that the different lengths are readily recognizable. As shown in Figs. 1 and 2, the 85 slots 11 may also be arranged in inclined relation relative to the lower edge of the pocket so that approximately the same proportion of the hairpin will be visible. Also the slots 11 are preferably of a size so that a 90 plurality of the hairpins can be inserted in each of the seats and also the pocket formed between the end flap 4 and section 2 can be employed for holding an additional supply of the pins thus permitting the device to be 95 used as a package for a considerable quantity of the articles. After the device has been filled the center section 3 is bent down over the pins and its end flap 5 return bent onto the back of the section 2. The point 7 and 100 tongue 6 are then inserted through the slot 8.

In the assembled position above described the contents are held firmly in place without the necessity of sealing the flaps thus permitting the package being mailed at the 105 lower postage rates and the pins or other articles will be strikingly brought to view upon opening the package. If desired, advertising matter as well as the name and address of the manufacturer of the articles 110 can be printed on the inner face of the flap 3 or any other desired portion of the con-

tainer. It will be noticed that the entire construction is one piece and the blank when formed and cut lies in a single plane so that any reading matter desired to be placed upon the container can be printed in the usual manner without the employment of special machinery.

The device is adapted for various uses, such as a selling package, an advertising mailing card for samples, an exhibiting device, and as a container for which the articles such as the hairpins can be kept in assorted sizes when not in use. While I have shown and described one embodiment of my invention, I do not desire to limit the invention to the exact details of construction shown nor in any manner except as specified in the appended claims.

I claim as my invention:

20 1. A combined container and exhibiting device for hairpins and the like, comprising a one-piece blank folded to form a central pocket, the inner wall of said pocket being apertured to provide a slot through 25 which the lower ends of a hairpin can be inserted, the position of the slot relative to the lower edge of the pocket being arranged to permit the upper end of the hairpin to project externally of the pocket, when 30 its lower end is supported by the lower edge of said pocket.

2. A combined container and exhibiting device comprising a one piece blank having a central section, an end section bent back on said central section, side flanges secured to said central section and adapted 35 to extend over the folded end flap, the latter having a slot through which the ends of

the articles are inserted to rest in the pocket thus formed while the upper portion of 40 the article extends on the outside of said end flap, a second central section adapted to fold down over said end flaps and said side flanges and means for securing the last mentioned central section in its folded 45 position.

3. A combined container and exhibiting device comprising a one piece blank having a central section, an end section bent back on said central section, side flanges 50 secured to said central section and adapted to extend over the folded end flap, the latter having a slot through which the ends of the articles are inserted to rest in the pocket thus formed while the upper portion of the 55 article extends on the outside of said end flap, and a second central section adapted to fold down over said end flap and said side flanges, the first mentioned central section having a slot and the last mentioned 60 central section having a tongue adapted when return bent to extend through the slot in the first mentioned central section and hold the parts in their folded position.

4. A combined container and exhibiting 65 device, comprising a one piece blank folded to form a pocket and a flap extending down over one of the walls of said pocket, said wall having a plurality of apertures forming 70 seats positioned at gradually increasing distances from the closed edge of the pocket to receive assorted sizes of articles with approximately the same relative proportion of each article being visible.

SOLOMON H. GOLDBERG.
